UNITED STATES PATENT OFFICE

138,391

DESIGN FOR A REFRIGERATED LOCKER UNIT

William McKinley Baird, Chicago, Ill.

Application May 8, 1944, Serial No. 113,511

Term of patent 14 years

(Cl. D67—3)

To all whom it may concern:

Be it known that I, William McKinley Baird, a citizen of the United States of America, residing at Chicago, in the county of Cook and State of Illinois, have invented a new, original, and ornamental Design for a Refrigerated Locker Unit, of which the following is a specification, reference being had to the accompanying drawing, forming a part thereof.

In the drawing:

Fig. 1 is a front perspective view of a refrigerated locker unit, showing my new design; and Fig. 2 is a rear perspective view thereof.

I claim:

The ornamental design for a refrigerated locker unit, substantially as shown.

WILLIAM MCKINLEY BAIRD.
